CLAIM

The ornamental design for a baseball glove, as shown and described.

DESCRIPTION

FIG. 1 is a rear perspective view of a baseball glove showing my new design.

FIG. 2 is a left side perspective view thereof.

FIG. 3 is a right side perspective view thereof; and,

FIG. 4 is a top elevational view thereof.

The broken line showing of a baseball glove is for illustrative purposes only and forms no part of the claimed design.
